UNITED STATES PATENT OFFICE.

GEORGE R. KELSEY, OF WEST HAVEN, CONNECTICUT.

BUCKLE-LOOP.

SPECIFICATION forming part of Letters Patent No. 227,541, dated May 11, 1880.

Application filed February 27, 1880.

To all whom it may concern:

Be it known that I, GEO. R. KELSEY, of West Haven, in the county of New Haven and State of Connecticut, have invented a new Improvement in Buckle-Loops; and I do hereby declare the following, when taken in connection with the accompanying drawings and the letters of reference marked thereon, to be a full, clear, and exact description of the same, and which said drawings constitute part of this specification.

Figure 1 shows the loop as applied to the suspender-end; Fig. 2, the blank from which the loop is formed; Fig. 3, section showing the loop as prepared for attachment; Fig. 4, transverse section attached to the suspender-end; Fig. 5, longitudinal section.

This invention relates to a loop for attaching suspender-ends to the buckle, the object being to form the loop and the clasp which engages the suspender-ends in a single piece; and the invention consists in the construction, as hereinafter described, and particularly recited in the claim.

From sheet metal a blank is cut, as seen in Fig. 2, the ring-shaped part A forming the

loop to the plate part B, to clasp around the suspender-end. The part B has a transverse rib, *a*, raised upon the inside, and the loop part A may be struck into a concavo-convex shape, so as to strengthen the loop. The part B is then struck into segment shape longitudinally, as seen in Fig. 1, but U shape transversely, as seen in Fig. 3, so as to permit the suspender-end to be laid therein. Then the edges of the tubular part are brought together and closed around the suspender-end. The rib *a*, impressing itself into the material of the suspender-end, forms a lock to prevent the movement of the end longitudinally.

I claim—

The herein-described buckle-loop, consisting of the loop A and plate B, in one and the same piece, the plate B constructed with the transverse rib *a*, and curved longitudinally and bent transversely, so as to inclose the suspender-end, substantially as described.

GEO. R. KELSEY.
